UNITED STATES PATENT OFFICE.

WILLIAM C. HOLIDAY, OF WEKIWA, FLORIDA.

SUSPENDERS.

1,259,984

Specification of Letters Patent. Patented Mar. 19, 1918.

Application filed March 30, 1917. Serial No. 158,600.

To all whom it may concern:

Be it known that I, WILLIAM C. HOLIDAY, a citizen of the United States, residing at Wekiwa, in the county of Lake and State of Florida, have invented a new and useful Suspenders, of which the following is a specification.

It is the object of this invention to provide novel means for limiting the movement 10 of a spring which, constituting a part of a pair of suspenders, serves to hold up the trousers or other garments.

It is within the province of the disclosure to improve generally and to enhance the 15 utility of devices of that type to which the present invention appertains.

With the above and other objects in view which will appear as the description proceeds, the invention resides in the combination 20 and arrangement of parts and in the details of construction hereinafter described and claimed, it being understood that changes in the precise embodiment of the invention herein disclosed can be made 25 within the scope of what is claimed, without departing from the spirit of the invention.

In the accompanying drawings:—

Fig. 1 shows in perspective, a pair of 30 suspenders constructed in accordance with the present invention, parts being broken away;

Fig. 2 is a perspective wherein a modified form of the invention appears;

Fig. 3 is an elevation showing a modified 35 form of the invention, parts being broken away;

Fig. 4 is a perspective view delineating a modified form of the invention;

Fig. 5 is an elevation illustrating a further 40 modification;

Fig. 6 is a front elevation showing a modified form of the invention;

Fig. 7 is a side elevation of the structure 45 shown in Fig. 6;

Fig. 8 is a front elevation showing a modified form of the invention; and

Fig. 9 is a side elevation of the structure shown in Fig. 8.

In carrying out the present invention 50 there is provided, as shown in Fig. 1, a pair of straps 1 bent upon themselves to form loops 2 and to define, in each strap 1, an inner layer 3 and an outer layer 4. The 55 layers 3 and 4 are extended downwardly

through a cam buckle 5 including an eye 6. The outer layer 4 is fashioned into a long loop 7, and the inner layer 3 is fashioned into a short loop 8 lying within the long loop 7. The ends of both loops are extended upwardly through the eye 6, and then downwardly, the depending ends 9 being stitched as shown at 10 to the back side of the short loop 8. The construction is such, obviously, that the effective length of the 60 depending forward ends of the straps 1 may be adjusted, without changing the difference in the lengths of the loops 8 and 7.

Suspended in the loop 8 is a holder 11 including an eye 12 with which is connected a retractile spring 14. A slide 15 is pivoted at 16 to the lower end of the spring 14. A suspension element in the form of a cord 17 is mounted to move endwise through the slide 15 and carries loops 18 adapted to be 70 assembled with the buttons of a pair of trousers.

When the spring 14 yields sufficiently, the slide 15 will come into contact with the bottom portion of the long loop 7, and thus the 75 elongation of the spring 14 will be limited. Because the difference in the lengths of the loops 7 and 8 remains constant when the buckle 5 is shifted, the amount which the spring 14 elongates before the slide 15 engages the bottom of the loop 7 remains constant also.

The loops 2 of the straps 1 are stitched or otherwise secured as shown at 19 to a back loop 18. The numeral 20 indicates a 80 spring the upper end of which is connected at 21 to the upper end of the loop 18. The lower end of the spring 20 is provided with a slide 22 which is pivotally mounted on the lower end of the spring as shown at 23. 95 Through the slide 22 works a suspension element in the form of a cord 23' having eyes 24 at its lower ends. When the spring 20 yields sufficiently, the slide 22 comes into contact with the bottom portion of the back 100 loop 18, and the elongation of the spring 20 is limited.

In Fig. 2 a modified form of the invention is shown. In said figure, the numeral 24' denotes a loop, such as the loop 7 or the 105 back loop 18. In this form of the invention, the suspension element or cord appears at 25 and has terminal eyes 26. One arm of the cord 25 may be provided with a branch 27 terminating in an eye 28. The eyes 26 110

are adapted to be engaged with the suspender buttons, and the eye 28 is adapted to be engaged with a nether garment.

In Fig. 3 of the drawings there is shown 5 a shoulder strap 29. One of these shoulder straps passes over each shoulder, and the shoulder straps meet in the back at a suitable point. With the shoulder straps, both at the front and at the back are assembled 10 adjustable buckles 30. The buckle 30 has a hook 31 engaged in an eye 32 on a holder 33 having hooks 34. A loop 35 is threaded through the holder 33. A retractile spring 36 is connected with the hooks 34. The lower 15 end of the spring 36 is provided with a hook 37 or other suitable element of any desired kind through which slides a cord 38 having eyes 39 at its ends. Assembled with the hook 37 or its equivalent is a ring 40 from 20 which depends a flexible element 41 mounted to slide in an opening 42 formed in the bottom of the loop 35. The lower end of the flexible element 41 terminates in an eye 43 which carries a spring clip 44 adapted to be 25 engaged with a nether garment. The loop 35 in this form of the invention serves as a limiting means, when the spring 36 is expanded.

In Fig. 4 of the drawings, a modified 30 form of the invention is shown. The construction shown at 45 is like that described in connection with Fig. 1, and the suspension elements 46 operate like the suspension elements 17. In this form of the invention, 35 however, the inner layer 47 and the outer layer 48 are separate pieces, the inner layer 47 terminating as shown at 49, short of the lower end of the outer layer 48. The outer layer 48 is extended to form a loop 50, the 40 end of which is stitched or otherwise held in place as shown at 51. A spring 52 is mounted in the loop 50 and carries at its lower end a slide or other element of a similar sort 53, the same being pivotally mounted. A single 45 cord 54 is connected with the parts 53 and passes downwardly through an opening 55 in the bottom of the loop 50, the cord 54 terminating in an eye 56.

In Fig. 5 of the drawings, the numeral 50 70 denotes inner layers which are stitched or attached otherwise as indicated at 63, to outer layers 60, it being evident that the layers 70 and 60 may be stitched together at any convenient point. The loop appears 55 at 61 and is stitched or otherwise attached, as shown at 62, to the layers 60. The flexible element appears at 64 and is provided with eyes 65, the spring construction preferably being like that shown at 52 and 53 in Fig. 4.

60 In Fig. 6 of the drawings there is shown a strap 100 bent upon itself to form a loop

101 having an adjustable end 102 carrying a button 103 adapted to be engaged in key-hole slots 104 formed in the body portion of the strap. At 105 there appears a retractile 65 spring carrying a button 106 which may also be engaged in any of the key-hole slots 104. The lower end of the spring 105 is provided with an eye 107 or the like, through which passes a flexible element 108 having loops 70 109 at its lower ends, it being obvious that the loop 101 constitutes a means for limiting the extension of the spring 105. Proper adjustments may be made by shifting the button 103 in the key-hole slots 104, and by 75 shifting the button 106 in the said key-hole slots.

In Figs. 8 and 9, a modified form of the invention is shown. In the said figures, there appears a strap 110 bent upon itself 80 to form a loop 111 the free end 112 of which is connected by a cam buckle 113, or otherwise, adjustably, with the strap 110. Mounted for adjustment on the strap 110 below the cam buckle 113 is a cam buckle 114 or 85 similar device, connected with a spring 115 having an eye 116 or other suitable means through which is threaded a flexible element 117, having loops 118 at its end. It is obvious that by manipulating the cam 90 buckles 114 and 115, the necessary adjustment can be obtained, as in the form shown in Figs. 6 and 7, saving for the fact that in Figs. 6 and 7 a step by step adjustment is provided for, whereas in Figs. 8 and 9, a 95 finer adjustment may be effected.

Having thus described the invention, what is claimed is:—

1. A device of the class described comprising a loop disposed in a single bight having an integral bend; a retractile spring supported at one end within the loop; a suspension element straddling the bend of the loop; and means at the other end of the spring for receiving the suspension element for longitudinal sliding movement, said means being adapted to engage with the bend of the loop to impose a positive limit upon the expansion of the spring.

2. A device constructed in accordance with 110 claim 1, in combination with a second suspension element attached at one end to said means and passing at its other end slidably through the bend of the loop.

In testimony that I claim the foregoing as 115 my own, I have hereto affixed my signature in the presence of two witnesses.

WILLIAM C. HOLIDAY.
